We claim:

The ornamental design for a microphone for dictating machine or the like, as shown.

FIG. 1 is a perspective view of a microphone for dictating machine or the like showing the top, one side and one end of our new design.

FIG. 2 is an elevational view of the microphone showing one side thereof.

FIG. 3 is a top plan view of the microphone.

FIG. 4 is an elevational view of the microphone showing the other side thereof.

FIG. 5 is an elevational view of the microphone showing one end thereof.

FIG. 6 is an elevational view of the microphone showing the other end thereof.

FIG. 7 is a bottom plan view of the microphone.
